UNITED STATES PATENT OFFICE

LOUIS M. LEVERONE, OF ALLSTON, MASSACHUSETTS

DESIGN FOR A SHOE

Application filed June 9, 1932. Serial No. 44,031. Term of patent 3½ years.

To all whom it may concern:

Be it known that I, LOUIS M. LEVERONE, a citizen of the United States, residing at Allston, in the county of Suffolk and State of Massachusetts, have invented a new, original, and ornamental Design for Shoes, of which the following is a specification, reference being had to the accompanying drawing, forming part thereof.

Fig. 1 is a view in side elevation and Fig. 2 is a plan view of a shoe showing my new design.

The dominant feature of my design resides in the ornamental effect produced by extending two straps crosswise of each other from

the shoe tip to the shank at each side of the sole, leaving an opening in front of the point where the straps are crossed and an opening between the edge of the tip and the straps at each side, said front opening being closed and said side openings partly closed by an underlying vamp of contrasting finish, from which a middle strap is extended to the ankle strap.

I claim:

The ornamental design for a shoe as shown and described.

In testimony whereof, I have signed my name to this specification.

LOUIS M. LEVERONE.
